UNITED STATES PATENT OFFICE

172,969

AIRPLANE

Clarence L. Johnson, Encino, Willis M. Hawkins, Jr., North Hollywood, and Eugene C. Frost, Burbank, Calif., assignors to Lockheed Aircraft Corporation, Burbank, Calif.

Application October 1, 1953, Serial No. 27,029

Term of patent 14 years

(Cl. D71—1)

To all whom it may concern:

Be it known that we, Clarence L. Johnson, Willis M. Hawkins, Jr., and Eugene C. Frost, all citizens of the United States residing at Encino, North Hollywood, and Burbank, respectively, in the State of California, have invented a new, original, and ornamental Design for an Airplane, of which the following is a specification, reference being had to the accompanying drawings, forming a part hereof.

Figure 1 is a perspective view showing the top, front and one side of an airplane embodying our new design;

Figure 2 is a perspective view showing the bottom, rear and other side thereof;

Figure 3 is a top plan view thereof;

Figure 4 is a front elevation thereof; and
Figure 5 is a side elevation thereof.

The landing gear has been omitted from Figure 2 for convenience of illustration.

The dominant features of our design reside in those portions shown in full lines.

We claim:

The ornamental design for an airplane, as shown and described.
